UNITED STATES PATENT OFFICE.

WILLIAM R. KRAMER, OF DELPHOS, OHIO.

WASHING-MACHINE.

SPECIFICATION forming part of Letters Patent No. 392,954, dated November 13, 1888.

Application filed March 9, 1888. Serial No. 266,688. (Model.)

To all whom it may concern:

Be it known that I, WILLIAM R. KRAMER, a citizen of the United States, residing at Delphos, in the county of Van Wert and State of Ohio, have invented certain new and useful Improvements in a Combined Washer and Stand; and I do declare the following to be a full, clear, and exact description of the invention, such as will enable others skilled in the art to which it appertains to make and use the same, reference being had to the accompanying drawings, and to the letters and figures of reference marked theron, which form a part of this specification.

15 This invention relates to a combined washer and stand, and has for its object the construction of a stand that can be readily adjusted within certain limits to increase or diminish its supporting-surface, and to provide an improved pounder and novel devices for reciprocating and rotating the pounder.

20 The improvement consists of the novel construction and combination of parts, which hereinafter will be more fully described and claimed, and shown in the annexed drawings, in which—

25 Figure 1 is a perspective view, parts being broken away, of a combined washer and stand embodying my invention, showing the stand adjusted by dotted lines; Fig. 2, a detail view 3c of one end of the cross-head, showing the means for connecting the pounder therewith.

35 The stand is composed of two corresponding frames or parts, A and B, which are constructed alike. The part A is composed of a triangular-shaped frame consisting of the converging sides A' A', the end A², the braces A³ A³, and the corner-posts A⁴ A⁴. The braces A³ extend from the middle of the end bar, A², to about the middle of the sides A'.

40 The upper edges of the sides extending from the ends of the braces to within a short distance of the ends of the sides are cut away about one-half the width of the sides for a purpose presently to be described. The part B

45 is composed of a triangular frame consisting of sides B' B', the end B², and the braces B³, and the corner-posts B⁴. The lower edges of the sides are removed, extending from the ends of the braces to within a short distance of the

50 ends of the sides and of a depth about equal to one-half the width of the sides. When the two

frames or parts A and B are put together, the reduced portions a and b of the sides A' and B' come opposite each other, the portion a being below the portion b, and the apices of the frames 55 stand in opposite directions. The post or standard C supports the apex of the frame B, and the apex of the frame A is supported by the bar B⁵, which extends from the end B² to the ends of the sides B'. The frame A is adapted 60 to move in and out to increase or diminish the size of the stand, as may be required, the end of A sliding on and being supported at all adjustments on the board B⁵.

65 The end of the standard C is reduced or provided with a pintle, c, on which is mounted the casting D. This casting has lugs d and d' on each side, the lug d being at a higher level than the lug d', and is free to rotate about the pintle, being held thereto by the pin d² when 7c it is desired to hold the casting in any desired position.

75 The hand lever E is pivoted to the casting, and is held about in a horizontal position by the spring F, which is made of a stout piece of wire that is doubled or folded midway of its ends, which ends are bent to form hooks that fit about the lower lugs, d', and pass up in the rear of and over the upper lugs, the free end of the spring being connected with the lever 80 by the hook f and the eye f'. The inner end of the lever E is slotted, and the pin e, that pivotally connects the lever E with the casting, passes through this slot e'. By this arrangement the lever is free to have a longitudinal 85 movement.

85 The pounder-shaft G extends through a vertical opening, e², in the lever E, and is threaded on its upper end to receive the nut g. The opening e² flares from its upper to its lower 90 end in the direction of the length of the lever to permit a free operation of the lever. The collar g, secured to the shaft G below the lever, is rounding on its upper side, so that it will not present any sharp edges which would wear 95 away the lever. The washer g², interposed between the nut g and the lever, is rounding on the side opposite the nut to diminish the friction between the washer and the nut and facilitate the operation of the lever. 100

The ratchet-wheel H, keyed to the shaft G, below the lever, is provided with crown-teeth

h, which are engaged by the pawl *h'* that is pivoted to the side of the lever. This pawl inclines slightly to a horizontal plane, and is provided at its free end with a side extension, 5 *h''*, which bears against the periphery of the wheel *H* and prevents any motion of the pawl inward that would disengage it from the ratchet-wheel.

The arm *I*, extending from the bracket, terminates in an eye, *i*, through which the shaft *G* works and is guided in its movements. The curved extension *I'*, projecting vertically from the arm *I*, is slotted, and this slot *i'*, which curves toward the casting, receives a pin, *e*³, projecting laterally from the lever *E*, which in its vertical movements receives at the same time a longitudinal movement, which movement is effected by the pin *e*³ riding in the curved slot *i'* of the extension *I'*.

20 The cross-head *J*, secured to the lower end of the pounder-shaft and having slots *j* at its ends, supports the pounders *K*, one pounder being at each end. The threaded stem *k* of each pounder extends through the slot *j* of the cross-head and is held in place by the nut *k'*. The upper side of the cross-head at each end is roughened, and the washer *k''*, interposed between the nut and the cross-head, is correspondingly roughened on the side adjacent to 30 the cross-head to prevent any slipping when the pounder is adjusted and the nut screwed home. The pounders set diagonally of the cross-head and can be adjusted to and from each other to suit the size of the vessel or tub, 35 and are semi-oval shaped in horizontal section. The perforated plates *k'*—two being provided for each pounder—meet near the bottom of the pounder and diverge as they extend upward.

40 The stand can be lengthened by drawing out the frame *A*, as shown by dotted lines in Fig. 1, and the lever can be swung around by withdrawing the pin *d*², as will be readily appre-

ciated. When the lever is moved up and down, it will cause in effect a vibratory movement of the shaft *G*. When the lever is descending, the pawl *h'* will ride over the teeth *h* of the ratchet-wheel *H*, and when the lever is ascending the pawl will engage with the said teeth and cause the shaft to rotate and change 45 the position of the pounders relative to the contents of the tub.

Having thus described my invention, what I claim, and desire to secure by Letters Patent, is—

55 1. A stand composed of two triangular-shaped frames having their apices extending in opposite directions, and having a portion cut away from the edges of the sides of each frame, whereby the two frames are adapted to move over each other, substantially as described.

2. The combination, with the two corresponding triangular-shaped frames having their sides halved together, of the corner-posts, 65 the post or standard *C*, and the bar *B*⁵, substantially as set forth.

3. The combination, with the casting, the lever pivoted to the casting and adapted to have a longitudinal movement, and the pounder 70 carried by the lever, of the arm *I*, and the curved extension arranged to engage with the lever and impart a longitudinal movement thereto simultaneously with its vertical movements.

4. The combination, with the lever, the pounder-shaft, and the arm *I*, of the extension *I'* and the pin *e*³, substantially as and for the purpose described.

75 In testimony whereof I affix my signature in presence of two witnesses.

WILLIAM R. KRAMER.
